(57) **CLAIM**

The ornamental design for a basket, as shown and described.

DESCRIPTION

FIG. 1 is a perspective view from above of a basket showing my new design;

FIG. 2 is a perspective view from below thereof;

FIG. 3 is front view thereof;

FIG. 4 is a back view thereof;

FIG. 5 is left side view thereof;

FIG. 6 is a right side view thereof;

FIG. 7 is a top view thereof;

FIG. 8 is a bottom view thereof; and,

FIG. 9 is a perspective view of an enlarged area from FIG. 2.

The dash-dot broken lines in FIGS. 2 and 9 depict enlargement boundary limits that form no part of the claimed design.

1 Claim, 6 Drawing Sheets
